UNITED STATES PATENT OFFICE.

PHILIP CHAPPELL BROWNE, OF PORTLAND, OREGON.

COMBINED LAMP AND HEATER.

1,335,650.

Specification of Letters Patent. Patented Mar. 30, 1920.

Application filed February 11, 1919. Serial No. 276,331.

To all whom it may concern:

Be it known that I, PHILIP CHAPPELL BROWNE, a citizen of the United States, and a resident of Portland, in the county of 5 Multnomah and State of Oregon, have invented a new and Improved Combined Lamp and Heater, of which the following is a full, clear, and exact description.

My invention relates to lamps and heaters, my more particular purpose being to provide a device of this general character and having means whereby it may be used either as a lamp for purposes of illumination or as a heater, and in each of these two respective capacities may be employed in a variety of different relations.

Reference is made to the accompanying drawings forming a part of this specification and in which like characters indicate 20 like parts in all the views.

Figure 1 is a side elevation of my device;

Fig. 2 is a substantially central vertical section through the same;

Fig. 3 shows the device when used as a 25 heater, certain parts being removed;

Fig. 4 is a section on the line 4-4 of Fig. 2 looking in the direction of the arrows; and

Fig. 5 is a fragmentary section of a part 30 of the casing.

A base 5 is provided with a neck 6 and with an annular flange 7 extending slightly inward from this neck. The base carries a spider 8. Secured to the base and extending 35 upwardly therefrom is a frame 9 having the general form indicated in Fig. 2. A casing made in two halves 10 is so fashioned as to fit against the frame 9. The two halves of the casing are each provided with a semi-ring 11 so formed that when the halves are together these semi-rings form a neck, as may be understood from Figs. 1 and 2. A loose ring 12 may be fitted upon this neck in order to hold the halves together, the ring 40 being movable vertically upward in order to disengage them. A cap 13 is provided with a reduced neck portion 13^a which fits upon the upper end of the neck made of the semi-rings 11 and as may be understood from 45 Fig. 2.

Carried by the cap 13 is a socket 14 in which are detachably fitted a pair of incandescent bulbs 15. Mounted rigidly upon the cap 13 and extending obliquely forward 50 therefrom, while diverging from each other, are a pair of arms 16 which support a shade

17. Another pair of arms 18 are carried by the socket 14 but are mounted to swing upon screws 18^a serving as trunnions or bearings. These arms 18 carry a reflector 19, which may be circular or parabolic as desired. By swinging the arms 18 downwardly, the reflector may be tilted to different angles and may be brought down into the extreme position indicated in Fig. 3. 65

Extending through the frame 9 is a shaft 20, and mounted upon one end of this shaft is a button 21 whereby the shaft and parts carried by it may be turned relatively to the frame. Mounted rigidly upon the shaft 20 70 are a pair of arms 22. Disposed between these arms and movable angularly in relation thereto is a heating element 23 having a cross-section of the general form shown in Fig. 4. This heating element is for the purpose of toasting or similarly heating articles. The heating element 23 carries a heating coil 24 and also a pendant rod 25. This rod is used as indicated in Fig. 3 for supporting the outer-edge portion of the heating element when the arms 22 are swung 75 into horizontal position. For this purpose the lower end of the rod 25 rests upon the floor or table supporting the base 5. The heating element 23 carries a number of stiff 80 wires 23^a serving as a grid. By means of screws 26 the heating element 23 may be tilted to different angles relatively to the arms 22 and secured in different angular positions. At 27 are a pair of wire racks, 85 suitable for supporting a slice of bread or the like to be toasted.

The base 5 is provided with an eye 28, and extending through this eye is a lamp cord 29 divided into two portions 30, 31. The 95 portion 30 passes upwardly through the spider 8 and divides into two wires 32, 33, which are connected to the arms 22, these arms, in turn being connected to the terminals of the heating coil 24. The portion 31 100 of the lamp cord leads up to the socket 14 and supplies the incandescent lamp bulbs 15 with current.

A pair of adjusting screws 18^a enable the operator to adjust the arms 18 in different 105 angular positions. Another pair of adjusting screws 19^a enable the reflector 19 to be adjusted and held in different angular positions as desired.

With the parts arranged as indicated in 110 Fig. 1, my device is suitable for use as an ordinary lamp. If the two halves 10 of the

casing be removed, as indicated in Fig. 3, the device is adapted for use as a heater. By turning the reflector 19 and shifting the angular positions of the arms 18 the heat 5 can be reflected and thus concentrated at any one of a number of a desired number of points, or may be projected to a distance, if desired.

By swinging down the arm 22 so that the 10 rod 25 rests upon the table, as indicated in outlines in Fig. 3, the device may be used as a toaster. For this purpose the heat received from the heating lamp 23 may be intensified, if desired, by aid of the reflector 19, which, of course, is shifted into an angular position suitable for the purpose. One 15 or more pieces of bread may be rested upon the rack 27, and thus positioned may be toasted by the heat from the heating element. For this purpose the arms 22 should 20 be vertical, as indicated by full lines in Fig. 3. If desired, however, these arms may be brought to horizontal position, as indicated by dotted lines in Fig. 3, and a piece of 25 bread to be toasted, or a pan of water or the like to be heated, may be rested directly upon the heating element.

I do not limit myself to the precise arrangement shown, as variations may be 30 made therefrom without departing from the spirit of my invention.

Having thus described my invention, I 35 claim as new and desire to secure by Letters Patent:

1. In a device of the character described, the combination of a supporting frame, a lamp and a heating element mounted there-

upon, means for turning said heating element into different positions relatively to 40 said supporting frame, and a reflector journaled upon said supporting frame and movable into different positions relatively to said lamp and to said heating element, said reflector being movable into one position for reflecting light from said lamp and into another position for reflecting heat from said 45 heating element.

2. In a device of the character described, the combination of a supporting frame, an electric lamp mounted thereupon, an electrically operated heating element mounted upon said frame, a pair of arms journaled upon said frame, a reflector carried by said arms and movable into two positions, one for reflecting light from said lamp and the 50 other for reflecting heat from said heating element, and means for holding said reflector in different positions of adjustment relatively to said arms.

3. A device of the character described 60 comprising a supporting frame, a swinging member mounted thereupon, a heating element carried by said swinging member and movable bodily into different positions relatively to said supporting frame, a lamp 65 mounted upon said supporting frame, a reflector common to said lamp and to said heating element, and mechanism connected with said reflector for holding the same in a position to enable it to reflect the light of 70 said lamp or in a position to reflect the heat of said heating element.

PHILIP CHAPPELL BROWNE.
